UNITED STATES PATENT OFFICE.

ALEXANDER JEFERSON KNOUSE, OF BENTON, PENNSYLVANIA.

RAIL-BRACE.

No. 893,928.

Specification of Letters Patent.

Patented July 21, 1908.

Application filed August 17, 1907. Serial No. 389,070.

To all whom it may concern:

Be it known that I, ALEXANDER JEFERSON KNOUSE, a citizen of the United States, residing at Benton, Columbia county, Pennsylvania, have invented certain new and useful Improvements in Rail-Braces, of which the following is a specification.

The invention relates to rail-braces and more particularly to that class which engage the opposite flange and web of a track section and are adjustable to provide for the correct fitting of the same to any rails; and also to prevent the lateral spreading of the latter.

15 The primary object of the invention is the provision of a brace for the engagement with opposite rails to prevent the spreading thereof when having been properly positioned in the road bed.

20 A further object of the invention is the provision of a brace to couple track-rails and by which the latter can be easily drawn together and separated from each other.

25 A further object of the invention is the provision of an adjustable brace for engaging track-rails and including flexible means associated with two clamp elements adapted to grip the track-rails, so as to obtain free movement of the said elements independent 30 of each other and also allow of their independent adjustment.

35 In event the track-rails should creep in either a forward or backward direction, due to the expansion and contraction of the material, the flexible connection means of the clamp elements will permit such movement and in no wise fracture or strain said elements, thus producing a flexible joint intermediate the same. Furthermore, this flexible 40 connecting means permits the two clamp elements to move freely inward with respect to each other, but, prevents lateral spreading of the same, and, thereby allows the track-rails to expand and contract created by the changes 45 in the temperature of the climate.

Another object of the invention is the provision of a rail or track-brace, simple, durable, efficient, and inexpensive in the manufacture.

50 In the drawing forming part of this specification I have shown one effective form of the embodiment of the invention which, to enable those skilled in the art to practice

the same, will be fully set forth in the following description, while the novelty of the invention will be included in the claims succeeding said description.

In the drawings, Figure 1, is a plan view of the invention applied to rails. Fig. 2, is a side view of the invention applied to the rails or track, the latter being shown in section. Fig. 3, is a sectional view of the loop member. Fig. 4, is a fragmentary perspective view of the loop member and clamp elements associated therewith.

65 Similar reference characters indicate corresponding parts throughout the several views in the drawings.

In the drawings, the numeral 2, indicates rails which are engaged by clamp elements, 70 as 3, the latter including rods, as 4, each having one end flattened, as 6, to receive the base of the rails 2, and thereby form a bearing surface. Said flattened portion 6, of each rod is bent on itself, as 7, to conform 75 to the shape of the flange and web of the rails to reinforce and strengthen the same. The opposite end of each rod 5, is provided with a screw-threaded terminal as at 8, which freely passes through an opening as 90 at 9, formed in either end of a loop member as at 10. In engagement with these threaded terminals of the rods 4, are threaded nuts as 11, and 12, the latter nuts adapted to lock the nuts 11, against movement when having been properly adjusted upon the rods 4.

In operation the clamp elements 3, are positioned with respect to the rails so that the latter will rest upon the flattened portion 6, of the rods 3, and lie contiguous to the bent 90 extremity 7. Now should it be desired to alter the position of either one of the rails it will be necessary to turn the lock nuts 12, to permit the movement of the nuts 11, then by adjusting the latter nuts upon the rods 4, the 95 clamp elements 3, can be shifted away from or towards each other. In this manner the rails will be properly positioned with respect to each other.

Should it be only necessary to adjust one 100 of the rails 2, this can be done by loosening nuts 11, and 12, on one threaded extremity of the rods 4, and then manipulating said nut 11, on the rod 2, until the desired adjustment has been made to bring the rails in 105 alignment with the remainder of the said rails.

It will be apparent that in event the rails on either side should creep on the ties the loop member 10, having loose connection at the ends of the rods 4, will prevent jamming 5 and the rods can be readily adjusted. Furthermore, it is obvious that the rods 4, at their threaded terminals 8, pass freely through the openings 9, in the loop member 10, and are engaged by nuts 11, and 12, 10 which have bearing at the inner side of said loop member, so that the clamp elements 3, will withstand a greater amount of lateral strain and weight before the rails will spread and in fact the loop member 10, would have 15 to break before spreading could occur or take place.

The threaded extremities of the rods 4, are not in threaded engagement with the loop member 10, and thereby, overcome the liability of the threads on the rods stripping therefrom, which will prevent the freeing of the said rods from connection with the loop member to allow accidental spreading of the rails, but, said rods 4, are held against accidental release from the loop member by the engagement of the nuts 11, and 12, upon the ends of the rods and arranged within the said loop member.

Having thus described the invention, what is claimed is:

1. A rail brace comprising oppositely disposed rods having threaded inner extremities and rail engaging outer extremities, an endless loop having opposed perforations, said threaded extremities being adapted to freely pass through said perforations and projecting a distance within said loop, and jam nuts engaging the threaded extremities of the rods, whereby the latter are flexibly connected to the said loop. 30

2. A rail brace comprising rods, each bent on itself to form a rail engaging extremity, the opposite end of each of said rods having screw threads, an endless loop containing opposite openings through which freely pass the threaded ends of said rods, and lock nuts on the threaded ends of said rods within the loop, whereby the rods are flexibly connected to said loop. 35

In testimony whereof I have hereunto set 40 my hand in presence of two subscribing witnesses.

ALEXANDER JEFERSON KNOUSE.
